J. BLACKBURN.

CABLE HANGER.

APPLICATION FILED AUG. 26, 1916. RENEWED JUNE 17, 1918.

1,288,485.

Patented Dec. 24, 1918.

UNITED STATES PATENT OFFICE.

JASPER BLACKBURN, OF WEBSTER GROVES, MISSOURI.

CABLE-HANGER.

1,288,485.

Specification of Letters Patent. Patented Dec. 24, 1918.

Application filed August 26, 1916, Serial No. 117,082. Renewed June 17, 1918. Serial No. 240,530.

To all whom it may concern:

Be it known that I, JASPER BLACKBURN, a citizen of the United States, and resident of Webster Groves, Saint Louis county, Missouri, have invented certain new and useful Improvements in Cable-Hangers of which the following is a specification containing a full, clear, and exact description, reference being had to the accompanying drawings, 10 forming a part hereof.

My invention relates to certain new and useful improvements in cable hangers or holders wherein a supporting device is provided for a cable, and further provided with 15 means in the form of hooks for suspension from a messenger wire.

A further object is to provide a hanger formed from a single piece of elastic wire by suitable automatic machinery, said hanger 20 being provided with a maximum contact surface when applied to the messenger to prevent creeping or sliding of the hanger over the messenger wire when the cable is being applied to the hangers.

25 A still further object is to construct a hanger which is used not only in the installation of new work, but may be applied for the support of existing cables, said hanger when in use having a series of supporting surfaces for the cable, so as to distribute the weight of the cable on more than one point.

With the above purposes in view, my invention consists in certain novel details of 35 the construction and arrangement of parts which will be hereinafter more fully described, pointed out in my claims and illustrated by the accompanying drawings, in which:

40 Figure 1 is a perspective view of my improved hanger or holder applied to a messenger or supporting wire, the cable being shown in dotted lines;

Fig. 2 is a perspective view of my hanger 45 being applied to a messenger wire, illustrating the method of applying the same; and

Fig. 3 is an end view looking in the direction of the arrow in Fig. 1.

Referring by numerals to the accompanying drawings:

4 designates the body portion of the hanger, which comprises two substantially U-shaped portions (in plan view) 5 and 6, which are arranged side by side, as illustrated, said portions in end elevation being

upwardly curved so as to provide a rounded or curved seat for the cable.

Formed integral with the U-shaped portion 5 is a branch arm 7, and formed integral with the U-shaped portion 6 is a branch arm 8, said arms 7 and 8 being curved in opposite directions.

The arm 7 is provided, near its terminal portion, with a bent portion 9, a substantially straight semi-elastic portion 10, and with a hooked portion 11, these portions just referred to acting as contact surfaces with the messenger or supporting wire when the same is applied for use.

The branch arm 8 is provided with an abruptly bent portion 12, which terminates in a substantially horizontal portion 13 and a hooked portion 14.

In the application of my improved holder or hanger the hooked portion 11 is first applied beneath the messenger or supporting wire, with the substantially straight portion 10 resting on the top surface of the messenger wire. When in this position the branch arm 8 is in front of the messenger wire, as illustrated in Fig. 2, and a downward force is applied until the hooked portion 14 passes beneath and in the rear of the messenger and is then engaged with it. The substantially horizontal portion 13 of the hooked portion 14 holds the hanger in position for use on the messenger.

It will be observed that my improved hanger has three contacts or gripping surfaces, namely, the bent portion 9, the substantially straight portion 10 and the hooked portion 11, thus providing sufficient contact surface to prevent the hanger or holder from movement on the messenger wire.

It will further be observed that my improved hanger has three supporting surfaces for the cable, thus distributing the weight of the cable to three points.

Having thus described my invention, what I claim as new therein and desire to secure by Letters Patent of the United States therefore, is:

1. A cable hanger, comprising a body portion formed of substantially U-shaped portions in plan and curved in end elevation, 105 arms formed integral with said substantially U-shaped portions and curved in opposite directions, one of said arms being provided with an inwardly bent portion, a substantially straight portion adapted to extend 110

over a messenger wire and a hooked portion adapted to extend beneath a messenger wire, and the other arm provided with a hooked portion adapted to engage the messenger wire.

2. A cable hanger, provided with a body portion on which a cable is adapted to rest, oppositely curved arms formed integral with said body portion, one of said arms being provided with a bent portion adapted to engage a messenger wire on its side, a substantially straight portion of greater length than the diameter of the messenger wire to which the hanger is applied arranged diagonally to the longitudinal axis of the messenger wire and adapted to engage it on its top surface and a hooked portion formed integral with said substantially straight portion adapted to engage a messenger wire on its lower surface, and the other of said arms having formed integrally therewith a hooked portion adapted to engage with the messenger wire.

3. A cable hanger, provided with a body portion, on which a cable is adapted to rest

and be supported, arms formed integral with said body portion, one of said arms being provided with a substantially straight portion, adapted to rest on the top of a messenger and disposed diagonally of the messenger, said substantially straight portion being provided with a hook adapted to rest beneath the messenger, a bend interjacent the arm and the substantially straight portion engaging the messenger in opposition to said hook, the other of said arms being provided with a substantially horizontal portion adapted to lie beneath and transversely of the messenger and held thereupon by the resiliency of the hanger, said substantially horizontal portion being provided with a hook for assisting in the support of the cable.

In testimony whereof, I have signed my name to this specification, in presence of two subscribing witnesses.

JASPER BLACKBURN.

Witnesses:

R. G. ORWIG,

E. L. WALLACE.
